PAPER BLANK FOR FORMING POSTCARDS

Jan van Mackelenbergh, 's Hertogenbosch,
NetherlandsApplication November 15, 1933, Serial No. 698,191
In the Netherlands November 17, 1932

1 Claim. (Cl. 229—92.8)

The present invention relates to paper blanks for forming articles for despatch through the post, in the nature of postcards, and it has for its primary object to provide an article which, after despatch and receipt by the recipient, can, in a simple way, be restored to the form of a single sheet of paper.

The paper blank in accordance with the invention comprises two portions separated by a fold at which the two portions can be separated by tearing, one of said portions serving as a copy sheet and the other portion being divided along the centre of its height by a folding line by which the said portion is divided into two sections, one adapted to carry the address and the other to carry the writing forming the desired communication, the said other portion being adapted to be folded along said folding line, whereupon the upper and the lower edges thereof can be fastened together to form the completed article for despatch.

The attached drawing shows the paper blank in accordance with the invention, indicating the manner in which it is used and in which:

25 Fig. 1 shows the complete blank,

Fig. 2 shows in front view, the sheet forming the blank which is folded double,

Fig. 3 shows in side view the double folded sheet as shown in Fig. 2,

30 Fig. 4 shows the postcard formed from the blank sheet in front view, and

Fig. 5 shows the card in side view.

As shown in Fig. 1, the paper sheet blank comprises two portions 1 and 2 which are connected at the centre by a folding line 3 along which the two portions 1 and 2 can be separated by tearing. The folding line can, for this purpose, advantageously be formed by an impressed line of weakening formed by a series of short dash-like elements.

40 The sheet 1 can be folded around the folding line 3 at the rear of the sheet 2 as shown in Figs. 2 and 3 and it is adapted to serve as a copy sheet.

The sheet 2, that is the front sheet, is, at the 45 centre of its height, provided with a folding line 4.

4. By means of this folding line, the front sheet is divided into an address section 5 and another section 6 adapted to bear the writing forming the desired communication.

50 After writing out the address and the desired communication and a copy thereof taken on the sheet 1, the latter sheet is separated along the fold 3. Then the sheet 2 is folded on itself along the folding line 4 as indicated in Figs. 4 and 5.

55 Finally, the edges 7 of the sheet 2 thus brought together are secured to one another, advantageously by means of a sealing machine in which, in the known way, the two sheet edges to be attached are drawn between two polished rollers running in the opposite directions. In this way

a postcard is obtained of the ordinary dimensions.

If the postcard is to be opened out after receipt, then the edges 7 are separated from each other, for example by drawing them between the 5 nails of the thumb and one finger or by tearing or pulling apart, whereby the said two edges are separated and an ordinary sheet of postal paper produced.

The paper blank according to the invention 10 has various advantages, which may be summarized as follows:

The postcard formed is constituted by ordinary paper and is therefore cheap. The copy sheet is fastened to the portion of the sheet 15 which forms the postcard and is therefore always ready for use. The copy is clearer than in the case of a postcard formed of card since the sheet on which the writing is performed is thinner. The copy sheet is stronger and larger than those 20 which are used with ordinary postcards and they can be therefore more easily and satisfactorily held in a letter file. The surfaces for the address and for the text lie in a single plane whereby reversal in the typewriter is made unnecessary.

The postcard to be despatched can be secured by perforation with teeth or by the impression of a name. The recipient of the postcard can easily open by pulling the fastening between 30 the nails of the thumb and one finger, whereby a sheet of normal size and thickness is obtained which can be placed in a letter file. The recipient of the card therefore does not have to insert a comparatively stiff card into his letter file, 35 which would hinder the turning over of the sheets.

The half letter or memorandum thus becomes unnecessary since the paper blank in accordance with the invention can be used in an envelope. 40 For this reason less types of letter paper are necessary in an office.

The paper blank in accordance with the invention can naturally also be used for those 45 cards bearing printed matter, of which copies must be taken.

What I claim is:

A paper blank for forming a postcard embodying an integral part adapted to serve as a copy sheet, the remainder of the blank after removal 50 of said part by tearing being foldable along a centre line to form the card for despatch by post, only the edges of said folded blank being secured together, permitting the folded blank to be fastened together to form a card suitable for postal 55 conveyance, the edges being adapted to be subsequently cut away or separated to permit the folded blank to be restored to its original sheet form.
